RUDOLF F. SCHOTT, OF SAN FRANCISCO, CALIFORNIA, ASSIGNOR TO CALIFORNIA BARREL COMPANY, OF SAN FRANCISCO, CALIFORNIA, A CORPORATION OF CALIFORNIA.

COVER-FASTENER FOR SHIPPING-PAILS.

1,358,253.

Specification of Letters Patent.

Patented Nov. 9, 1920.

Application filed April 5, 1920. Serial No. 371,304.

To all whom it may concern:

Be it known that I, RUDOLF F. SCHOTT, a subject of Germany, residing at the city and county of San Francisco and State of California, have invented certain new and useful Improvements in Cover-Fasteners for Shipping-Pails, of which the following is a specification.

The hereinafter described invention relates to means for securely attaching the cover to shipping pails adapted to contain merchandise generally for shipment from the wholesaler to the retail dealer, although it is more particularly designed for use in connection with pails employed in the shipment of candy, and the same is designed to seal the cover to the pail in such a manner as to provide against the removal of the contents thereof during transit without causing a mutilation of the sealing means.

Heretofore, it has been customary to secure the sealing or securing wires for the cover to the wooden tubs or pails in various ways, in some cases by securing the terminal ends of the wires to the inner surface of the tub or pail and extending the wires through bores formed in the staves thereof, again, the terminal ends have been attached to the projecting loop portion of staples driven into the tub or pail: also the terminal ends of the said wires have been secured beneath the upper hoop of the pail or tub. Each of these methods of attaching the terminal ends of the securing wire is open to serious objections, inasmuch as considerable time is required to properly attach the terminal ends of the wires where the loop staples and the hoop are employed as the securing means for the wires, and further the loop staples do not provide against the withdrawal thereof and the hoop may be worked in such a manner as to permit the freeing of the securing wires and an opening of the package for the partial removal of contents therefrom, and in each of these cases the attaching means may be restored to normal position, so that when the pail or tub is received by the consignee, mutilation of the seal will not be present, although the package was opened in transit and a portion of the contents removed. The objection to the formation of bores in the staves of the pail for the passing of the terminal portions of the securing wires

therethrough is twofold, first, the expense 55 incident to the formation of such bores, and, secondly, the openings thus provided permits of air and dust passing therethrough to have access to the contents of the sealed tub or pail, again, the securing wires cannot be 60 readily threaded through bores or holes.

The object of the present invention is to provide a simple, inexpensive and efficient means for securing the cover to the tub or pail, and doing so in such a manner as to 65 overcome the objections to the employment of the described means commonly employed for securing the cover in position relative to the pail.

To comprehend the invention, reference 70 should be had to the accompanying sheet of drawings, wherein—

Figure 1 is a perspective view of an ordinary wooden shipping pail with the improved fastening means applied thereto and 75 sealed.

Fig. 2 is an enlarged sectional detail view illustrating the manner of attaching the terminal ends of the securing wires to the 80 staves of the pail.

Fig. 3 is a perspective view of one of the corrugated saw-edged attaching or fastening plates utilized for uniting the securing wires to the tub.

In the drawings, the numeral 1 is used to 85 designate the tub to be sealed, preferably disclosed circular in form, 2 the cover therefor, 3 the pair of securing wires for the cover, and 4 the seal for uniting the wire together over the cover of the pail. 90

The terminal end portions 5 of each securing wire 3 is firmly embedded within the staves of the pail by means of an attaching plate 6, which is corrugated as shown at 7 and provided with a saw edge 8. These attaching plates are approximately one-half an inch in length and are driven for their full distance into the wooden staves of the pail, so that their outer edge is substantially flush with the surface of the pail. 100

In attaching the securing wires to the pail, an attaching plate is placed over the wire adjacent an end thereof and driven into the stave of the pail its full distance and when so driven carries the wire therewith, so that 105 when properly positioned the end portion of the securing wire is forced into the wood surface of the pail approximately one-half

an inch and firmly held therein by reason of the fact that it embraces each face of the corrugated fastening or attaching plate 6, Fig. 2 of the drawings. In thus attaching a securing wire, the same is placed on the surface of the pail with its terminal ends upwardly positioned, so that when secured to the pail it is only required to upwardly raise the central portion thereof to cause the 10 portion adjacent the terminal or attached end to overlie the fastening plate. Inasmuch as the said fastening plates are of corrugated form, the same when driven into the wood are firmly and securely held therein 15 against removal. There are no looped extensions exposed by this type of fastening or attaching plate, as are provided where ordinary staples are employed and to which the terminal ends of the securing wires as here- 20 tofore employed are united, as for instance the loop 9 of the staples 10 employed for uniting the bail 11 of the pail. There is no means employed under my invention which may be withdrawn to permit the removal of 25 the securing wires, without causing a mutilation of the sealing means.

When the securing wires have been attached as herein described, the pail filled and the cover 2 placed thereon, the wires are 30 brought together over the cover, drawn taut and united one to the other by means of a suitable seal 4. Thus, the only manner provided for a release of the cover 2, is either

by a removal of the seal or the destruction of the securing wires. 35

The attachment of the securing wires is such that they in no manner interfere with the nesting of the pails, when shipped unfilled to purchasers thereof.

Having thus described the invention what 40 is claimed as new and desired to be protected by Letters Patent is:—

1. In combination with a shipping pail, of securing wires for holding the cover to the pail against removal during transit, fastening plates driven into the pail substantially 45 flush with the surface thereof and embedding the terminal end portions of the securing wires in the staves of the pail, and sealing means for uniting the securing wires one 50 to the other.

2. In combination with a shipping pail, of fastening plates formed with corrugated surfaces and a saw edge adapted to be driven into the pail members substantially flush 55 with the surface thereof, securing wires for holding the cover to the pail against removal during transit, said wires having the terminal end portions thereof embedded in the staves of the pail by the fastening plates so 60 as to overlie said plates when drawn upwardly over the pail, and means for uniting the wires one to the other.

In testimony whereof I have signed my name to this specification.

RUDOLF F. SCHOTT.
